(57) **CLAIM**

The ornamental design for a reversibly installable shower enclosure, as shown and described.

DESCRIPTION

FIG. 1 is a perspective view of a reversibly installable shower enclosure, shown mounted in the right-hand hinged configuration;

FIG. 2 is a front elevational view of FIG. 1;

FIG. 3 is a rear elevational view of FIG. 1;

FIG. 4 is a top plan view of FIG. 1;

FIG. 5 is a side elevational view of FIG. 1; and,

FIG. 6 is a similar perspective view to FIG. 1, but with the invention shown mounted in the left-hand configuration.

As the top and bottom plan views are identical only one is shown. Further, it is noted that as the right side and left side elevational views are mirror images of one another only one is shown. No additional information would be added hereto by showing the various views of the FIG. 6 configuration. The broken lines are for illustrative purposes only and form no part of the claimed design.
